(Cl. D67—3)

FIG. 1

FIG. 2

Figure 1 is a front perspective view of an absorption refrigeration unit for chilling water or the like embodying my new design; and

Figure 2 is a view in elevation of the unit illustrated in Figure 1 taken from the left-hand side of the machine.

The rear of the unit is substantially plain and the side not shown is substantially like the side shown.

I claim:

The ornamental design for an absorption refrigeration unit for chilling water or the like, substantially as shown and described.
